UNITED STATES PATENT OFFICE.

CALVIN JELF, OF OPDYKE, ILLINOIS.

BALL-BEARING SELF-CLOSING HINGE.

1,324,505.

Specification of Letters Patent.

Patented Dec. 9, 1919.

Application filed April 22, 1918. Serial No. 230,164.

To all whom it may concern:

Be it known that I, CALVIN JELF, a citizen of the United States, residing at Opdyke, in the county of Jefferson and State 5 of Illinois, have invented certain new and useful Improvements in Ball-Bearing Self-Closing Hinges, of which the following is a specification containing a full, clear, and exact description, reference being had to 10 the accompanying drawings, forming a part hereof.

My invention relates to an improved gravitating (or self-closing) anti-friction hinge, and it consists in the novel construction and arrangement of parts hereinafter specified, and substantially as pointed out in the claim found at the end of this specification.

The object of my invention is to provide 20 an efficient, reliable and low-priced anti-friction hinge, which can be applied to door-screens, window-screens, doors and other parts of a building which are hung upon hinges, and which are self-closing.

25 In the drawings,

Figure 1 is a front elevation of my improved hinge, ready for attachment to a door or other swinging part of a structure.

Fig. 2 is a similar view, with the two 30 leaves slightly separated, in order to show the anti-friction bearing between the adjacent ends of the knuckles or pintle-sockets.

Fig. 3 is a top plan view of the hinge.

Fig. 4 is an inverted plan-view of the upper anti-friction bearing member, looking in 35 the direction indicated by the line 4-4 of Fig. 2, and

Fig. 5 is a plan-view of the lower anti-friction bearing member, detached, and 40 looking in the direction indicated by the line 5-5 of Fig. 2.

In manufacturing hinges in accordance 45 with my invention, all that is necessary is to provide the usual form of mating leaves 1 and 2 of any known material, and of any known and approved shape, having the screw or nail holes 3 through which fastening-means (such as the usual screws or 50 nails) are passed for the purpose of securing the hinge to the door to be hung and to the door frame; and then provide such leaves with the anti-friction devices which are now to be described.

Formed integral with the leaf 1, at the 55 inner edge thereof, is a cylindrical boss or knuckle 4, which has the usual vertical bore

through it for the passage of the usual headed pintle 5, and which boss is the upper member of the anti-friction bearing of the hinge.

Depending from the lower end of said boss or knuckle 4 is an annular water, snow and dust shield 6, which incloses the upper end of the lower knuckle 7 carried by the opposite leaf 2, and keeps the rain, snow and dust from entering the semicircular spiral ball-race 8 which is formed in the upper end of the said lower knuckle, and in which a free ball (or similar anti-friction device) is adapted to roll bodily from 65 end to end of said race and support the weight of the upper knuckle and all of the weight that is imposed upon it by the door or other article that is hung by the hinge, which latter is of course to be 70 used in pairs, as is usual in all ordinary hinges known to me. By the term "semicircular spiral ball-race" I mean that said ball-race 8 is semicircular or curved in cross-section, as well as spiral in form. (See 75 Fig. 5).

By making said ball-race curved in cross-section the said ball 9 will be retained in said race by the walls of the latter throughout the length of the ball-race, thus preventing 85 the ball from "jumping" out of the race at any point.

But the said ball-race being curved in cross-section and placed open side up, it would be very soon filled with dirt, which 90 would prevent the practical operation of said ball 9, were it not for the protecting function of the said downwardly extending shield 6, which latter being formed integral with the said upper knuckle 4 projects 95 around and incloses and protects the entrance to the said ball-race.

Furthermore, the outer wall of said ball-race, being comparatively thin and weak, is protected from breakage by accidental 100 blows which would be delivered upon said wall were it not for the protection afforded by the said shield 6.

This renders the construction very strong and durable, and yet the weight of the parts 105 is comparatively light, so that there is not a wastage of metal in making the castings very heavy.

Said anti-friction device may be a ball 9, or any mechanical equivalent that is adapted 110 for the purpose.

The said upper member or knuckle 4 has

upon its lower end a smooth flat spiral surface 10, at the lower end of which is a circular recess 11 that is a little larger in size than the size of the said ball 9, and in this recess the said ball is located at all times, and rolls around therein as the weight of the upper member 4 and the part of the door or other hung article carried by it is exerted downwardly. By reason of the fact that the said circular recess 11 is located at the end of the said smooth flat spiral surface 10, as above described, the said ball is thereby prevented from going beyond said recess.

Said circular shield 6 is cast integral with the upper knuckle 4, and entirely incloses and embraces the said flat spiral surface 10 of said knuckle, thereby strengthening and protecting the edges of said spiral surface, as well as depending below the plane of the same to inclose and protect the said outer wall of said ball-race 8 of the lower knuckle 7.

When the door or other hung article is swung open the said ball 9 rolls upwardly upon and along the said spiral ball-race 8 in said lower knuckle 7, to a point adjacent the upper end of said ball-race; and when the door is being closed the said ball 9 moves in a reverse direction in said ball-race.

It will be evident that the weight of the door will cause the moving parts to gra-

tate, and thereby cause the door and hinges to automatically close and stay closed until opened again.

Further description of the operation is deemed unnecessary.

I claim the following as my invention:

The improved gravitating hinge, comprising suitable mating leaves; an upper knuckle cast integral with one of said leaves, and having upon its lower end a flat spiral surface, at one end of which is a circular recess, said knuckle also having the usual pintle-bore; a lower knuckle having in its upper end a spiral ball-race curved in cross-section; a ball located in said ball-race, but stopped against movement upon said flat spiral surface by said circular recess at said recess-end of the flat spiral surface; and an integral circular shield inclosing and protecting the outer edge of said flat spiral surface, and depending from the lower end of said upper knuckle a sufficient distance to inclose and protect the outer wall of said spiral ball-race of said lower knuckle.

In testimony whereof, I have signed my name to this specification in presence of two subscribing witnesses.

CALVIN JELF.
